PROTECTIVE MEANS FOR CONVEYERS

Emory R. Woodring, McKeesport, Pa.

Application August 10, 1948, Serial No. 43,462

3 Claims. (Cl. 198—52)

1

This invention relates to a protective means for cushioning the fall of materials discharged from a chute.

An object of the invention is the provision of a protective and cushioning means for a belt conveyor which is adapted to receive abrasive materials from the lower end of a chute, the protective means being in the form of a length of belting having a free end projected forwardly of the lower end of the chute and onto the upper run of the conveyor while the other end of said belting is rolled on a drum, means being employed for retaining the free end projected at all times on the conveyor so that the materials will fall onto the free end of the belting and prevent wear of the belt conveyor.

A further object of the invention is the provision of a protective means for a belt conveyor in which the free end of a length of belting is drawn from a drum and projected onto the conveyor where materials having an abrasive action are discharged from the lower end of a chute so that the free end of said belting will receive the falling materials and protect the conveyor from wear, the worn free end of the belting being removed from time to time and replaced by unrolling the belting sufficiently from the drum, a resilient element being employed for retaining the belting taut between the drum and the free end and for maintaining said free end projected in an operative position on the upper run of the conveyor.

The invention is best understood from a consideration of the following detailed description in connection with the accompanying drawings, nevertheless, it is to be understood that the invention is not confined to the disclosure but is susceptible of such changes and modifications as shall define no material departure from the salient features of the invention as expressed in the appended claims.

In the drawings:

Figure 1 is a side view in elevation of my attachment applied to a chute and in protective relation with a belt conveyor.

Figure 2 is a plan view of the attachment.

Figure 3 is an enlarged fragmentary vertical section taken along the line 3—3 of Figure 2.

Figure 4 is a view in perspective of a flanged collar for rotatably supporting the opposite ends of a shaft square in cross section.

Figure 5 is an enlarged transverse vertical section taken along the line 5—5 of Figure 2, and

Figure 6 is an enlarged fragmentary longitudinal section showing the cushioning means for

2

an auxiliary belt forming the main element of the attachment.

Referring more particularly to the drawings 10 designates a conveyor belt supported by a drum 11. The upper run of the belt which is driven in the direction indicated by the arrow in Figure 1 is supported by spaced rollers 12 along its length. A chute 13 directs coke on to the upper run of the belt. The coke has an abrasive action 10 on the belt and such abrasive action is increased by the height of the lower end of the chute above the belt and also by the fact that the coke leaving the end of the chute is traveling faster than the conveyor.

15 A protective means for the belt consists of a length of belting 15 supported by the bottom of the chute with a free end 16 resting on the upper run of the moving belt conveyor and at a point on the conveyor where the chute would ordinarily 20 discharge the materials onto said belt so that the free end of the length of belting will bear the abrasive action of the materials. The length of belting 15 is guided by a plurality of brackets 17 and 18 as said belting is played out from a drum 25 20. However, the length of belting is carried primarily by a plurality of bolts or rollers 21 and 21a which are connected between the lower ends of pairs of the brackets secured at 22 on the side walls of the chute 13 and depending therefrom.

25 A resilient means for the length of belting 15 is employed for maintaining the free end 16 of said belt projected forwardly on the upper run of the belt 15 at the initial discharge of materials from the chute and during the continuous 30 pouring of the materials from the chute and particularly when the force of the discharging materials acts on said free end. The resilient means includes one or more springs 25 attached to the length of the belting. The cushioning of the belting tends to check the speed of the coke or other materials before being received by the upper run of the belt 10. One coil spring may be employed but two or more springs will prevent any tendency to lateral shifting of the free end 16 of the belting since the tension on said end will be distributed across the width of said belting. It will be noted from Figure 6 that one end of the coil spring or springs is attached to the transverse bolt 21 while the other end of 45 said spring has been converted into a hook 26 which is received within a slot 27 in the length of belting.

The drum 20 is mounted on a shaft 30 which is square in cross section and which is received 50 by square-shaped openings 31 in the closed ends

32 of said drum. The shaft is in line with the longitudinal axis of the drum. A bushing 33 consists of a collar 34 and a circular flange 35. The collars are received by circular openings 36 in supporting plates 37 which depend from the side walls 38 of the chute 13. The upper ends of the plates are bolted at 39 and 39a to said walls. The collars are revolved by the shaft since the shaft is received by a passage 40 square in cross section, in the collar and flange. The closed ends of the drum are in abutting relation with the flanges 35.

A ratchet wheel 45 has a square central opening received by the shaft 30. The outer end of one collar 34 abuts one face of the wheel while the inner end of another collar 46 abuts the outer face of said wheel. A bracket 47 has its upper end secured to the spaced supporting plate 37 by the bolts 39a. The lower end of said bracket is provided with an opening 48 receiving the collar 40 which is rotatable therein. A flange 50 on the collar is in contact with the outer face of the bracket. A collar 51 is secured at 52 to one end of the shaft 30 while a collar 53 is secured at 54 to the other end 55 of the shaft. The collar 51 at the other end of the shaft has an integrally formed operating crank 56. A pawl 57 depending from a pivot 58 on the supporting plate 37 adjacent the ratchet wheel 46 prevents reverse rotation of the wheel.

The length of belting 15 at its inner end is attached to the drum 20 in any approved manner and the drum is prevented from playing out said belting by the pawl 57 and ratchet wheel 45 attached to the shaft 30. The springs 25 which are connected between the belting and the bolt 21 maintain the free end 16 of the belting extended over that portion of the upper run of the conveyor 10 where the materials are discharged from the lower end of the chute 13. When coke or other hard abrasive materials are discharged directly on to the conveyor, such conveyor becomes worn. This wearing action is increased further by the fact that the speed of the falling materials is greater than the speed of the moving conveyor. The free end of the belting cushions the fall of the materials and rolls said materials onto the conveyor.

When the free end 16 of the belting becomes worn, the pawl is released and the drum 20 is revolved in the direction indicated by the arrow in Figure 3 to play out a further portion of the free end of the belting to replace the worn section of the belting. It is to be borne in mind that the hooks 26 on the springs 25 must be released from the slots 27 in the belting 15 before any adjustment of the belting is made. After a sufficient portion at the free end of the belting has been projected forwardly over the conveyor 10 the hooks are replaced in slots located inwardly of the slots 27.

The springs maintain the belting 15 taut on the drum. In other words, said springs exert a pull on the belting for not only retaining a free end 16 projected over the conveyor but for taking up any slack in the belting between the drum and the projected free end of the length of belting.

What I claim:

1. In an endless conveyor for transporting loose abrasive mineral matter which is discharged onto the conveyor from the lower end of a chute, means protecting the conveyor from the falling materials comprising a length of belting having the free end thereof projected onto the upper run of the conveyor to receive the materials before being discharged onto said run, a manually rotated drum arranged transversely of said chute intermediate the ends thereof and dependingly supported by said chute, the other end of the belting being attached to the drum with the slack portion of the belting being wound thereon, a spring connected between the chute and the belting adjacent the free end of said belting for taking up slack and for maintaining the free end of the belting projected onto the conveyor and a releasable means retaining the drum against rotation.
2. In an endless conveyor for transporting loose abrasive mineral matter which is discharged onto the conveyor from the lower end of a chute, means protecting the conveyor from the falling materials comprising a length of belting having the free end thereof projected onto the upper run of the conveyor to receive the materials before being discharged onto said run, a manually rotated drum arranged transversely of said chute intermediate the ends thereof and dependingly supported by said chute, the other end of the belting being attached to the drum with the slack portion of the belting being wound thereon, spaced guides depending from the chute for supporting the belting between the free end thereof and the drum, a spring connected between one of the guides and an intermediate portion of the belting for maintaining the free end of the belting projected onto the upper run of the conveyor, and a releasable means for retaining the drum against rotation.
3. In an endless conveyor for transporting loose abrasive mineral matter which is discharged onto the conveyor from the lower end of a chute, means protecting the conveyor from the falling materials comprising a length of belting having the free end thereof projected onto the upper run of the conveyor to receive the materials before being discharged onto said run, a manually rotated drum arranged transversely of said chute intermediate the ends thereof and dependingly supported by said chute, the other end of the belting being attached to the drum with the slack portion of the belting being wound thereon, spaced guides depending from the chute for supporting the belting between the free end thereof and the drum, one of the guides being located adjacent the discharge end of the chute, a coil spring having one end connected to the last-mentioned guide, a hook on the other end of the spring received by an opening disposed in the belting between the drum and the free end of said belting for maintaining said free end projected over the conveyor, and a releasable means for retaining the drum against rotation.
